UNITED STATES PATENT OFFICE.

WILLIAM J. CURRY, OF NETTLETON, MISSISSIPPI.

MUCK-SHOE.

1,343,436.

Specification of Letters Patent. Patented June 15, 1920.

Application filed September 5, 1919. Serial No. 321,844.

To all whom it may concern:

Be it known that I, WILLIAM J. CURRY, a citizen of the United States, residing at Nettleton, in the county of Lee and State 5 of Mississippi, have invented certain new and useful Improvements in Muck-Shoes, of which the following is a specification.

This invention relates to an improved muck shoe for horses and has as one of its 10 principal objects to provide a device of this character which may be readily attached or detached and which will prevent a horse from sinking into mud when passing over swampy or marshy land.

15 The invention has as a further object to provide a muck shoe wherein, when desired, carks may be readily attached thereto for preventing slipping.

And the invention has as a still further 20 object to provide a device of the above described character which may be locked upon the shoe of a horse and wherein the locking device employed will be resiliently held in locked position so that possibility of accidental loss of the shoe will be reduced to a 25 minimum.

Other and incidental objects will appear hereinafter.

In the drawings:

30 Figure 1 is a perspective view showing my improved muck shoe attached to a conventional type of horseshoe,

Fig. 2 is a longitudinal sectional view taken centrally through the device, and

35 Fig. 3 is a fragmentary plan view particularly illustrating the locking lever employed for securing the muck shoe upon the horseshoe, parts being broken away and shown in section.

40 In carrying the invention into effect, I employ a preferably flat body or plate 10 which, at its forward end portion is deflected upwardly and is preferably provided with rounded corners. Also, the rear corners of the plate are preferably cut off so 45 that sharp angles will be eliminated. Upstanding from the plate adjacent its forward end is a medially arranged arcuate toe plate 12. This plate is provided at its lower edge with a plurality of laterally directed lugs 50 and engaging through these lugs are rivets or other suitable fastening devices securing the toe plate to the body plate. As best shown in Fig. 2 of the drawings, the toe 55 plate is inclined rearwardly and upwardly from the body plate. Mounted upon the

body plate adjacent one rear corner thereof is a heel plate 14 riveted or otherwise secured to the body plate and having upwardly bent portions providing a socket 15. 60 Mounted to swing upon the body plate at a point opposite the heel plate 14 and adjacent the other rear corner of the body plate is a locking lever 16. At its rear end portion this lever is thickened to form a head 65 17 and engaging through the head is a bolt or other suitable fastening device 18 pivotally connecting the lever with the body plate. At its forward end, the head is cut away at its inner side to provide a socket 19, 70 a forwardly extending flange 20 overhanging said socket. As particularly illustrated in Fig. 3, the lever 16 is curved longitudinally, and formed on the lever at its forward end is a depending lug 21 merging at 75 its inner end into an upstanding thumb piece 22 curving laterally outward with respect to the lever. The lever is preferably formed of suitable resilient material and, as shown in Fig. 1, the lug 21 is resiliently held by 80 the shank of the lever to engage through an opening 23 in the body plate for locking the lever closed in active position.

In order that a clear understanding may be had of the manner in which my improved 85 muck shoe is applied, I have, in the drawings, shown the device in connection with a conventional type of horseshoe 24. As will be observed, the toe plate 12 is curved to snugly receive the toe portion of the 90 horseshoe and will extend upwardly at the front of the horse's hoof to coact therewith while the socket 15 of the heel plate 14 will snugly receive one end of the shoe. The 95 opposite end of the shoe will be snugly received within the socket 19 of the lever 16, the flange 20 engaging over the shoe at its adjacent end and the lever conforming to the curvature of the shoe at its outer edge to abut thereagainst. The device will thus 100 be securely held upon the shoe of the horse. In applying the device, the lever 16 is first swung outwardly when the toe plate 12 is engaged at the front of a hoof of the horse. The device is then moved to engage the adjacent end of the horseshoe in the socket 15 of the heel plate 14. The lever 16 is then 105 swung inwardly to engage the flange 20 of the lever over the horseshoe at its other end when the lug 21 of the lever will snap into the opening 23 for securing the lever closed and locking the device upon the 110

horseshoe. It will accordingly be seen that the device may be easily applied and since a locking means is provided for the lever 16, possibility of accidental displacement of the device will be reduced to a minimum. The spacing of the toe plate, heel plate and locking lever may, of course, be varied for different sized horseshoes, it being intended that the device shall be furnished in different sizes to suit varying requirements.

In connection with the body plate 10 of the device, I provide removable calks 25 therefor which may be used when desired for preventing slipping. These calks may, 15 as particularly illustrated in Fig. 2, each be formed from a piece of sheet metal bent upon itself and having its overlapping portions flattened against each other, the calks being of a length to extend throughout the 20 major portion of the width of the body plate. Formed on the calks at their upper edges are spaced pairs of oppositely directed lateral flanges 26, and removably engaging through these flanges are bolts or other suitable fastening devices 27 detachably connecting the calks to the body plate. Thus, 25 the calks may be readily secured in position and as easily removed. As will be noted, the front calk is preferably arranged in advance of the plane of the toe plate 12 while the rear calk is disposed slightly at the rear of the plane of the heel plate 14 and rear end of the lever 16.

Having thus described the invention, what 35 is claimed as new is:

1. A device of the character described including a shoe body, a toe plate upstanding therefrom to coact with the toe of a horseshoe, a heel plate carried by the shoe body to 40 coact with one heel portion of a horseshoe, and a lever carried by the shoe body to coact with the other heel portion of a horseshoe for connecting the shoe body thereto and movable to a position locking the device 45 upon the horseshoe.

2. A device of the character described including a shoe body, a toe plate upstanding therefrom to coact with the toe of a horseshoe, a heel plate carried by the shoe body 50 to coact with one heel portion of a horseshoe, a lever carried by the shoe body to coact with the other heel portion of a horseshoe for connecting the shoe body thereto, and means for locking the lever in active 55 position.

3. A device of the character described including a shoe body, a toe plate upstanding therefrom to coact with the toe of a horseshoe, a heel plate carried by the shoe body 60 to coact with one heel portion of a horseshoe, and a lever pivoted upon the shoe body and formed with a socket for receiving the other heel portion of a horseshoe for connecting the shoe body thereto, the lever being 65 provided with means to coact with the

shoe body for locking the lever in active position.

4. A device of the character described including a shoe body, means upstanding therefrom to coact with the toe of a horseshoe, means carried by the shoe body to coact with one heel portion of a horseshoe, and a resilient lever pivoted upon the shoe body and provided with means to coact with the other heel portion of a horseshoe for connecting the shoe body thereto, the lever being provided with locking means yieldably held by the lever to coact with the shoe body for securing the lever in active position.

5. A device of the character described including a shoe body provided with an opening, means upstanding therefrom to coact with the toe of a horseshoe, means carried by the shoe body to coact with one heel portion of a horseshoe, and a lever carried by the shoe body and provided with means to coact with the other heel portion of a horseshoe for connecting the shoe body thereto, the lever being provided with a lug engageable in said opening for locking the lever in active position.

6. A device of the character described including a shoe body, means upstanding therefrom to coact with the toe of a horseshoe, means carried by the shoe body to coact with one heel portion of a horseshoe, and a lever mounted to swing upon the shoe body and provided with a head recessed to form a socket for receiving the other heel portion of a horseshoe for connecting the shoe body thereto, said lever being formed with a depending lug adapted to coact with the shoe body for locking the lever in active position.

7. A device of the character described including a shoe body, an arcuate toe plate upstanding therefrom to coact with the toe of a horseshoe, a heel plate upstanding from the shoe body and provided with a socket for receiving one heel portion of a horseshoe, and a lever mounted to swing upon the shoe body and provided with a recess for receiving the other heel portion of a horseshoe for connecting the shoe body thereto, the shoe body being provided with an opening and the lever being formed with a depending lug engageable in said opening for locking the lever in active position.

8. A device of the character described including a shoe body, means for detachably connecting the shoe body with a shoe of a horse, and removable elongated and transversely extending calks at the toe and heel portions of the shoe body, each of said calks being formed from a piece of material having its marginal portions bent into overlapping relation and provided with flanges secured to the shoe body for connecting the calk thereto.

In testimony whereof I affix my signature.
WILLIAM J. CURRY. [L.S.]
